(57) **CLAIM**

The ornamental design for a dead weight pressure relief manifolds for pressure fryers, as shown and described.

DESCRIPTION

FIG. 1 is a perspective view of a left-hand mounted, dead weight, pressure relief manifold for a pressure fryer, according to an embodiment of the design.

FIG. 2 is a perspective view of a right-hand mounted, dead weight, pressure relief manifold for a pressure fryer, according to an embodiment of the design.

FIG. 3 is a top view of the dead weight, pressure relief manifold of FIGS. 1 and 2, according to an embodiment of the design.

FIG. 4 is an end view of the dead weight, pressure relief manifold, according to an embodiment of the design.

FIG. 5 is a front view of the dead weight, pressure relief manifold of FIGS. 1 and 2, according to an embodiment of the design.

FIG. 6 is a right side view of the dead weight, pressure relief manifold of FIG. 2, according to an embodiment of the design.

FIG. 7 is a left side view of the dead weight, pressure relief manifold of FIG. 1, according to an embodiment of the design.

FIG. 8 is a bottom view of the dead weight, pressure relief manifold of FIGS. 1 and 2, according to an embodiment of the design; and,

FIG. 9 is a perspective view of the dead weight, pressure relief manifold of FIG. 1, according to an embodiment of the design, mounted on a pressure fryer.

The broken lines shown in the drawings are for illustrative purposes only and form no part of the claimed design.
